Charles Buckland
Sectary Patent 93302 X

No. 25.

The Schedule referred to in the foregoing Patent and making part of the same containing a description of in the words of the said Charles Buckland himself of his improvement in the machinery for cutting grooves in Corset-rings and other articles to all to whom this present shall come.

Be it known that Charles Buckland of Middlebury in the County of Middlesex and State of Connecticut have invented a new and useful improvement in Machinery for cutting grooves in Corset-rings of bone, ivory, or other substances and grooves in rings, wheels and round blocks of any other material in description and that the following is a full and exact description of the construction and operation of the said Machine as invented or improved by me.

A frame of cast iron called the bed (Marked A in the annexed drawings) twelve inches long and eight and a half inches wide is fastened to a bench with screws. On one of the frames, and on its rails is fitted another frame of cast iron (Marked B) seven and a half inches long and five and a half inches wide and so adjusted as to slide on the rails at pleasure.

This inner frame is composed down to the rails by means of two iron plates (Marked C.C.) with screws called the slide-rod. On the side of the slide-rod opposite to the front part of the frame are fitted two small rods of iron and on these rods two special springs so that as the operator pushes the slide-rod from him these springs by their elastic construction enable him to move the slide-rod steadily up to the rail or cutting

On the top of the slide rest is fitted a receding shaft (Marked D) on the end whereof the end of ring of plate to be cut; and as the operator pushes the slide rest towards the saw the end of the shaft runs against a double incline which ~~is~~ ^{guides} the ring upon the ends of the shaft, holds it while saw cuts the groove.

This being done the slide rest is withdrawn and in returning the other end of the incline comes in contact with the inside of the ring and crowds it off, leaving the shaft ready to receive another ring when it is pushed up forward to the centre of the incline. The incline is directly under the end of the shaft and is marked E in the drawing. On the inside of the bed rest on the centre of the back nail there is fitted a small block of wood (Marked F) and is used as a gauge and stopper. If the slide rest is moved up to the stopper the groove in the ring will be cut sufficiently deep and the groove in all the rings will be precise alike. On the sides of the saw are cut two notches below the teeth, these are small projections which comes in contact with the sharp edges of the rings and gives them a receding of sort of guides. Instead of a saw or cutter a chisel may be substituted.

The preceding description enables the machine with its various proportions as I at present see it. But it may be made of any other convenient materials, and although I see the machine for cutting the groove in, cast rings of bone and ivory, morally that it may be applied and I claim the privilege of applying it to the cutting of grooves in rings which are round blocks of any size or material. The machine with suitable gearing may be operated by water or any other adequate power. I do not claim any

any of the parts of the said Machine taken separately, as my invention, but I do claim as my invention and improvement - the combination of the several parts of the said Machine in the manner above specified, to produce and thereby producing the effect of cutting with rapidity, neatness and uniformity, grooves in Collet rings of bone, ivory or other substances, and grooves in rings, wheels and round blocks of any other material or description. Dated at Middleton the tenth day of August G.A.D. 1835.
